UNITED STATES PATENT OFFICE.

JOSEPH A. STEINMETZ, OF PHILADELPHIA, PENNSYLVANIA.

SUBMARINE WARFARE.

1,222,498.

Specification of Letters Patent. Patented Apr. 10, 1917.

Application filed March 22, 1916. Serial No. 86,036.

To all whom it may concern:

Be it known that I, JOSEPH A. STEINMETZ, a citizen of the United States, residing at Philadelphia, in the county of Philadelphia and State of Pennsylvania, have invented certain new and useful Improvements in Submarine Warfare, of which the following is a specification, reference being had therein to the accompanying drawing.

- 10 The object of this invention is to provide for enabling submarine vessels to defend or attack by means of gases adapted to incapacitate for normal activity those who breathe the same. This end is sought in 15 providing for releasing from the submarine suitable gases either by the action of persons in the submarine or by projectiles from or ramming by any hostile craft, the operator controlled release taking place while the 20 under-water craft is submerged, and the idea being that one submarine, or preferably several submarines, first getting on the windward side of a hostile ship or ships may release a large quantity of temporarily incapacitating gas which will move along the 25 water and envelop, and penetrate all openings on each ship and practically put the same out of action by seriously interfering with the efforts of all persons thereon.
- 30 Figure 1 is a diagrammatic view illustrating an embodiment of the invention, and Figs. 2 and 3 are small detail views hereinafter explained.

In these figures, A represents a vessel of 35 any non-submersible kind and B a submarine of any approved type, having a suitable periscope C of recognizable or usual form. Upon the exterior of the submarine are detachably secured a series of very large tanks 40 D containing suitable gas and each preferably provided at one end with a periscope-like tube E similar in appearance to the periscope C. Each tank is shown as held between hinged arms which are normally 45 prevented from opening by any suitable well known device F released by an electric current through wires G coming from the interior of the vessel. Each tube E is preferably closed by a diaphragm H adapted to 50 be broken by an electric current through conductors I from the interior of the vessel, the current acting through any suitable devices; *e. g.*, detonating a small explosive charge at J. These tanks may be thus released at will either after destruction of 55 their closures or without such destruction,

or, if desired, the closure may be destroyed without releasing the tank or tanks. In the former case, the released tank rises by flotation to the surface of the water and if previously opened discharges gas. If unopened, it may probably draw attack because indistinguishable from the periscope of a submarine, and if hit by a projectile the gas is at once set free. If the closure is destroyed 60 and the tanks are not freed from the submarine, the gas itself rises to the surface of the water and spreads out thereon with much the same result as in the cases first mentioned.

Fig. 1 shows one of the freed tanks as having reached the surface of the water after having its closure destroyed and as having its upper end ruptured by hostile attack so that it discharges gas through the 70 periscope-like tube and also through the rupture, and further shows a second released tank as rising from the submarine toward the surface of the water. The tanks are preferably provided with weights K at their 75 lower ends so that they assume a vertical position in the water, and this weight may, if desired, be utilized for opening the tank when the latter reaches a vertical position. The weight may primarily be held in a 80 chamber below the gas space, the chamber having, below, a marginal flange for retaining it until the tank approaches vertical position.

The gas tanks may be released from the 85 submarine by non-electrical means operated from inside the submarine and when reaching proper or chosen surface position the tanks may be opened by a pull on the control line N leading from the submarine, thus preventing the gas tanks from floating away from the field of operation. The tanks may, if desired, be provided with an annular external chamber O near the end bearing the 90 tube E to insure their assuming an upright 95 position in the water.

Heretofore, so far as I am aware, submarines have been used in attack only for launching torpedoes and for attack with deck guns when not submerged. Broadly, the invention involves freeing from a submerged vessel large quantities of incapacitating gases to spread out above the surface of the water and thereby to put surface craft out of action. It is quite possible to provide the submarine with normally closed 100 openings or pipes M and to provide for dis-

charging through such openings or pipes the gases carried or generated within the submarine or a compartment thereof.

It is obvious that submarines may, by liberating gases, attack hostile craft and by night even more effectively and with more complete safety for themselves, and by night or day can, if it be desirable, escape very readily while the attention of dangerous enemies is devoted to consideration of incapacitating gas.

What I claim is:

1. The method of attacking hostile floating craft which consists in providing a submarine with a great volume of gas unsuitable for ordinary respiration and discharging the gas, by means operated by persons within the submarine while the latter is submerged, into the open atmosphere just above the surface of the water and near the vessel to be attacked.
2. The combination with a submarine, of a gas tank secured upon the exterior of the submarine and adapted to hold a large supply of incapacitating gas, and means controlled by those within the submarine for allowing said gas to pass rapidly into the free air above the submerged submarine.

3. The combination with a submarine, of a large gas tank secured externally thereto and containing a great volume of incapacitating gas, means controlled from within the submarine for opening the tank, and means for freeing the tank and allowing it to rise to the water's surface.

4. The combination with a submarine provided with external gas tanks containing a large volume of incapacitating gas, of electric means operable from within the submarine to open the tanks and to free them and allow them to float to the water's surface while the submarine remains submerged.

5. The combination with a submarine of a large external gas tank releasably held upon the submarine and provided at one end with a normally closed pipe simulating a submarine's periscope, and means for maintaining said pipe in substantially vertical position when the released tank floats at the surface of the water.

In testimony whereof I affix my signature in presence of two witnesses.

JOSEPH A. STEINMETZ.
